UNITED STATES PATENT OFFICE.

JOSEPH JOHNSON, OF EAST ST. LOUIS, ILLINOIS.

CYLINDER HEAD.

Application filed December 23, 1926. Serial No. 156,678.

This invention relates to cylinder heads of a type primarily intended for use in connection with internal combustion engines, and it is an object of the invention to provide a structure of this kind embodying a frictionless valve action.

Another object of the invention is to provide a head of this kind constructed in a manner whereby the spark plugs are effectively cooled and wherein is avoided the necessity of providing a cooling medium above the combustion chamber provided in the head.

A further object of the invention is to provide a head of this kind which is constructed in a manner to eliminate compression shock and wherein the valve action embodies a spherical or ball-like valve member.

A still further object of the invention is to provide in a cylinder head a valve action constructed and operating in a manner to eliminate friction thereby increasing engine efficiency by taking less engine power to operate the valve action.

An additional object of the invention is to provide a head with a valve action which, during the time of compression or combustion and power stroke, operates in direct association with anti-friction bearings, thus eliminating liability of sticking.

The invention consists in the details of construction and in the combination and arrangement of the several parts of my improved cylinder head whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a view partly in section and partly in elevation illustrating a cylinder head and associated valve action constructed in accordance with an embodiment of my invention;

Figure 2 is a sectional view taken substantially on the line 2-2 of Figure 1.

As disclosed in the accompanying drawings, B denotes the upper portion of a cylinder block having produced therein a desired number of cylinder bores 1 in each of which a piston is adapted to have reciprocating movement in a well known manner. As the

features of the piston and the elements associated therewith form no part of my present invention it is not believed a detailed description and illustration thereof is necessary.

Applied to the block B and held thereto in any desired manner is a head H constructed in accordance with an embodiment of my invention. This head H comprises a lower section X and an upper section Y bolted, as at 2, or otherwise secured one to the other. The lower section X is provided in its under portion with the conoidal explosion or combustion chambers 3 each being in direct register with a cylinder bore 1. The upper or apex portion of each of these chambers 3 is open to provide a port 4. The upper or apex portion of the wall of each combustion chamber 3 extends within a depression or pocket 5 provided in the upper face of the lower section X of the head and the apex end edge of the wall of the chamber 3 being formed to provide a seat with which snugly engages the spherical or ball-like valve member M. This member M is keyed, as at 6, to a shaft section 7 disposed radially through the member M and extending a desired distance beyond opposite sides thereof.

The upper portion of the pocket or depression 5 has its wall parti-spherical, as indicated at 8, and which portion is closely approached by the member M.

The extended portions of the shaft section 7 are in direct contact with the ball bearings 9 suitably retained by the sections X and Y, 90 preferably through the medium of the grooved raceways 10. It being understood that the opposed faces of the sections X and Y are grooved to permit the requisite application therebetween of the extended portions of the shaft section 7.

The member M is also partially received in a parti-spherical pocket or recess 11 provided in the under face of the section Y, the wall of such pocket or recess being provided with grooves or channels 12 in which are retained the ball bearings 14 with which the valve member M contacts. Through the medium of the bearings 9 and 14 it will be evident that a valve member M is capable of 105 rotation with the substantial elimination of frictional resistance which is particularly desirable during compression and explosion.

At a point in relatively close proximity to the port 4 the section X of the head H is 110 provided with the ports 15 and 16 in communication with the pocket or depression 5, the

port 15 as herein disclosed constituting an intake port and the port 16 constituting an exhaust port.

The valve member M is provided at diametrically opposed points in its periphery with the grooves 17 the base wall *a* of which being preferably disposed from end to end on an inbow of requisite radius. Each of these grooves or channels 17 is of a length 10 to provide a bypass which, as the member M is rotated, will place the port 15 in communication with the port 4 and in proper sequence place the port 4 in communication with the port 16.

15 In practice, all of the members M are adapted to rotate in unison and in the same direction and, as herein disclosed, this is accomplished by having the opposed shaft sections coupled one to the other, as indicated 20 at 18, in any desired manner, the opposed faces of the sections X and Y being provided with registering recesses or cavities 19 to permit such coupling of adjacent shaft sections before the section Y is applied to the section X.

30 Each of the combustion chambers 3 at diametrically opposed points is provided with the openings 20 to permit the requisite placement of the spark plugs 21 and the section X above such openings 20, and in close proximity thereto, and below the ports 16 is provided with a jacket 22 in which is adapted to be circulated in any desired manner water or other cooling medium. The arrangement 35 of this jacket 22 is such to assure effective and desirable cooling of the applied spark plugs 21.

40 Arranged within the lower portion of each of the pockets or depressions 5 is a packing ring 23 having its inner marginal portion formed, as at *b*, for close contact with the periphery of a valve member M and such contact is maintained through the instrumentality of the spring members 24 arranged within 45 the pocket or depression 5 below or inwardly of the ring 23 and operating to constantly urge the ring 23 toward and in contact with the periphery of the member M. Each of these spring members 24, as particularly illustrated in Figure 2, is of triangular form as occasioned by the converging walls of the chamber 3 and the lower portion of the pocket or depression 5.

55 The upper portion of the pocket or depression 5, or that part immediately above the parti-spherical portion 8, is of increased diameter, as indicated at 25, and in which is received a second or upper packing ring 26 the inner marginal portion of which being 60 formed in close contact with the periphery of the valve member M. It is to be noted that the maximum internal diameter of the ring 26 is less than the diameter of the member M so that said packing ring 26 is held from 65 passing upwardly or outwardly beyond the

member M. The under or inner surface of this ring 26 is provided therearound with a groove or channel 27 in which extends a resilient member 28, such as an undulated ring or washer, which serves to constantly urge 70 the ring 26 outwardly and in requisite close contact with the periphery of the member M. In order to compensate for the extended portions of the shaft section 7 the ring 26 at diametrically opposed points is provided with 75 suitable depressions although this will not be necessary if the enlarged portion 25 is of requisite depth to position the ring 26 entirely below the shaft section 7. It is to be noted, however, that in any event the enlarged portion 25 is of such depth to provide requisite clearance to assure the desired contact of the ring 26 with the member M.

This enlarged portion 25 is substantially closed by the arcuate plates 29 which are 80 effectively maintained in applied or working position by the upper section Y of the head H. It is also to be understood that the ring 26 and the plates 29 are applied in working position before the section Y is assembled 85 with respect to the section X.

It is thought to be obvious that by having the jacket 22 arranged as hereinbefore referred to means may be conveniently applied for effective lubrication of the various anti-friction members or ball bearings.

90 One of the shaft sections 7 extends beyond the head H and such extended portion, as illustrated in Figure 1, carries a gear 30 adapted to be suitably connected with the crank 100 shaft or other movable part of the motor to effect the desired timed rotation of the members M.

95 From the foregoing description it is thought to be obvious that a cylinder head 105 constructed in accordance with my invention is particularly well adapted for use by reason of the convenience and facility with which it may be assembled and operated, and it will also be obvious that my invention is 110 susceptible of some change and modification without departing from the principles and spirit thereof and for this reason I do not wish to be understood as limiting myself to the precise arrangement and formation of 115 the several parts herein shown in carrying out my invention in practice except as herein-after claimed.

I claim:

120 1. A cylinder head comprising two over-lying sections, means for connecting said sections together, one of said sections in its under portion being provided with a conoidal explosion chamber for register with a cylinder bore when the head is applied, the upper portion of the wall of said chamber being 125 open, the upper portion of said lower section being provided with a pocket into which the upper portion of the wall of the chamber extends, the upper portion of the wall of the 130

5 pocket being parti-spherical, a spherical valve member coacting with the parti-spherical portion of the wall of the pocket, the free edge of the portion of the wall of the explosion chamber extending within the pocket constituting a seat for said valve member, said lower section being provided with intake and outlet ports for communication with the explosion chamber through the open end of the chamber within the pocket, the second head section having a parti-spherical portion in which is received a portion of the valve member, means for rotating the valve member, said valve member having means for 10 placing the intake and outlet ports in proper sequence in communication with the explosion chamber, a packing ring arranged within the lower portion of the pocket for close contact from below with the applied valve member, and spring members arranged within the pocket and contacting with the side wall of the pocket, the portion of the wall of the explosion chamber extending within the pocket and with the packing ring for urging the packing ring into contact with the valve member.

2. A cylinder head comprising two overlying sections, means for connecting said sections together, one of said sections in its under portion being provided with a conoidal explosion chamber for register with a cylinder bore when the head is applied, the upper portion of the wall of said chamber being open, the upper portion of said lower section being provided with a pocket into which the upper portion of the wall of the chamber extends, the upper portion of the wall of the pocket being parti-spherical, a spherical valve member coacting with the parti-spherical portion of the wall of the pocket, the free edge of the portion of the wall of the explosion chamber extending within the pocket constituting a seat for said valve member, said lower section having a parti-spherical portion in which is received a portion of the valve member, means for 15 rotating the valve member, said valve member having means for placing the intake and outlet ports in proper sequence in communication with the explosion chamber, the upper portion of the pocket in the lower section immediately above the parti-spherical portion thereof being of increased diameter, a packing ring arranged within said portion, said ring being of a diameter to bring the inner marginal portion thereof in close contact with the periphery of the valve member, the internal diameter of the ring being less than the diameter of the valve member, and spring means contacting with the bottom face of the packing ring for constantly urging the same into contact with the valve member.

4. A cylinder head comprising two overlying sections, means for connecting said sections together, one of said sections in its under portion being provided with a conoidal explosion chamber for register with a cylinder bore when the head is applied, the upper portion of the wall of said chamber being open, the upper portion of said lower section being provided with a pocket into which the upper portion of the wall of the chamber extends, the upper portion of the wall of the pocket being parti-spherical, a spherical valve member coacting with the parti-spherical portion of the wall of the pocket, the free edge of the portion of the wall of the explosion chamber extending within the pocket constituting a seat for said valve member, said lower section being provided with intake and outlet ports for communication with the explosion chamber, a packing ring arranged within the lower portion of the pocket for close contact from below with the applied valve member, and spring members arranged within the pocket and contacting with the side wall of the pocket, the portion of the wall of the explosion chamber extending within the pocket and with the packing ring for urging the packing ring into contact with the valve member, each of said spring members being triangular in form.

65 3. A cylinder head comprising two overlying sections, means for connecting said sections together, one of said sections in its under portion being provided with a conoidal explosion chamber for register with a cylinder bore when the head is applied, the upper portion of the wall of said chamber being open, the upper portion of said lower section being provided with a pocket into which the upper portion of the wall of the chamber extends, the upper portion of the wall of the pocket being parti-spherical, a spherical valve member coacting with the parti-spherical portion of the wall of the pocket, the free edge of the portion of the wall of the explosion chamber extending within the pocket constituting a seat for said valve member, said lower section being provided with intake and outlet ports for communication with the explosion chamber through the open end of the chamber within the pocket, the second head section having a parti-spherical portion in which is received a portion of the valve member, means for rotating the valve member, said valve member having means for placing the intake and outlet ports in proper sequence in communication with the explosion chamber, the upper portion of the pocket in the lower section immediately above the parti-spherical portion thereof being of increased diameter, a packing ring arranged within said portion, said ring being of a diameter to bring the inner marginal portion thereof in close contact with the periphery of the valve member, the internal diameter of the ring being less than the diameter of the valve member, and spring means contacting with the bottom face of the packing ring for constantly urging the same into contact with the valve member.

intake and outlet ports in proper sequence in communication with the explosion chamber, the upper portion of the pocket in the lower section immediately above the parti-
5 spherical portion thereof being of increased diameter, a packing ring arranged within said portion, said ring being of a diameter to bring the inner marginal portion thereof in close contact with the periphery of the
10 valve member, the internal diameter of the ring being less than the diameter of the valve

member, spring means contacting with the bottom face of the packing ring for constantly urging the same into contact with the valve member, and arcuate plates arranged outwardly of the packing ring for substantially enclosing the enlarged portion of the pocket, the applied second section holding said plates in position.

In testimony whereof I hereunto affix my 20
signature.

JOSEPH JOHNSON.
